UNITED STATES PATENT OFFICE.

JOSEPH MOLTCHEN, OF THE UNITED STATES ARMY.

COMBINED PICTURE-PROJECTING AND SOUND-REPRODUCING MACHINE.

1,277,991.

Specification of Letters Patent. Patented Sept. 3, 1918.

Application filed April 28, 1917. Serial No. 165,218.

To all whom it may concern:

Be it known that I, JOSEPH MOLTCHEN, of the United States Army, and a citizen of the United States, residing at Jefferson Barracks, Missouri, have invented certain new and useful Improvements in Combined Picture-Projecting and Sound-Reproducing Machines, of which the following is a specification containing a full, clear, and exact description, reference being had to the accompanying drawings, forming a part hereof.

My invention relates to an improved self-contained instrument for the production and transmission of sound, and more particularly to the transmission of speech in connection with moving pictures and their visual display.

The object of my invention is to provide an improved single instrument, in which shall be contained and combined in compact form, and driven in unison, a graphophone, Victrola, or other common form of talking-machine, and a moving-picture projector, as well as a suitable screen upon which the pictures will be exhibited to audiences, in the home, or in halls.

My invention consists in the novel construction and combination of the several parts as hereinafter described and particularly designated in the claim found at the end of this specification.

In the drawings,

Figure 1 is a top plan view of an instrument embodying my combination (in one form) of a talking-machine, a moving-picture projecting machine, and a screen movably mounted to slide upon the frame of the machine.

Fig. 2 is a sectional side-elevation of the machine or instrument, the section being taken on the line 2—2 of Fig. 1.

Fig. 3 is a detail sectional plan-view of the combined horn and screen slide chamber, the section being taken on the line 3—3 of Fig. 2.

Fig. 4 is a detail transverse vertical section, taken through the talking-machine and its combined horn and screen-slide chamber, on the line 4—4 of Fig. 1.

Fig. 5 is a detail vertical section of a portion of the inner vertical wall of the combined horn and screen-slide chamber, and showing a common lens mounted in an aperture formed in said wall, and

Fig. 6 is a front view of a piece of the picture film.

The numeral 1 designates a suitable base-frame or casing for the support of the combined talking-machine, moving-picture machine, and combined horn and screen-slide chamber, and which base-frame may be of any desired material and exterior ornamentation, as may be best suited to the use of the instrument in the home, or in public halls.

A common talking-machine turn-table 2 is mounted (in the present form of my invention) upon the usual vertical spindle, and is driven by the bevel-gears 3 and horizontal shaft 4, sprocket-wheel 5 and a "silent" chain 6 of common form, connected to any suitable form of motor 7 by the sprocket-wheel 8 on the motor shaft; all of which parts are located above the combined horn and screen-slide chamber 9, and the latter being located above and supported by the said base-frame 1.

Within said horn chamber 9 is mounted to slide in suitable guides 10, in telescopic relation to the said guides, a combined sliding horn and screen-slide 11.

Said slide 11 extends out of said chamber 9 through a suitable opening in the front vertical wall of said chamber, and carries at its outer end a screen-frame 12, in which is stretched a common screen 13, of fabric, or any suitable material.

The rear (or inner) end of the said combined sliding horn and screen-slide 11 is open, to receive the sounds from a fixed-horn 14, located in said horn chamber 9 in the rear of said sliding part 11, and to permit passage of rays of light from the lens 15 which is fixed in the aperture 16 of a vertical partition 17, which separates the said chamber 9 from the projecting-machine chamber 18. (See Fig. 5.)

The talking-machine is fitted for the usual records 19, and has the well-known sound-box 20 and needle, as well as the swinging tapered horn-tube 21, the latter being connected to the interior of the said fixed horn 14 by a fixed vertical tube 22 extending through an aperture formed in the top of said chamber 9 downwardly to the said fixed-horn.

Within the projecting-machine chamber 18 is located a common moving-picture projecting machine, having the usual lantern 110

23 (which may be of electric or other form); the upper film magazine 24; the lower film-magazine 25; and the usual film-moving mechanism case 26, as well as the lens-tube 27.

From said film-moving case 26 I extend a horizontal drive-shaft 28 through an aperture in the vertical side-wall of the said chamber 18, and on said shaft I fix a 10 sprocket-wheel 29 over which runs said chain 6, to drive the film-moving mechanism synchronously with respect to the movement of the said talking-machine record 19. In case it is desired to run the machine by hand, a hand-crank 30 is located on the outer end of said shaft 28.

In order to deaden the noise of the machinery as much as possible, so that it will not interfere with the speech and other 20 sounds produced by the talking-machine, I cover the interior of the walls of the narrow vertical chamber 31 (in which the said sprocket-wheels 5 and 8 and a great part of the sprocket-chain 6 are located) with a 25 series of superposed layers of sound-deadening padding 33; and besides I line the internal walls of the projecting machine chamber 18 with the same, or similar, material, in order that the noise of the running 30 machinery therein will be confined as much as possible to that chamber.

With my machine, as above described, the standard moving-picture film 32, or a smaller film, may be used; but on all films I 35 provide a "starting mark" 34, drawn or imprinted transversely of the film at the starting-point, to accurately inform the operator of the exact location of the first picture to be exhibited synchronously with the appropriate sounds produced by the talking machine record, which latter is also provided 40 with a "starting mark" 35 on its face, to register with a fixed mark 36 made on the upper face of the said turn-table 2.

45 The operation of my invention will be obvious to those skilled in the art.

It will reproduce the music of any musical-instrument, or of orchestras and bands, as well as talking-sketches, vaudeville, operas, and all other sounds produced by the 50 human voice, simultaneously and in synchronism with appropriate pictures of moving objects on said screen 13.

The said screen 13 (or the entire slide and horn 11) may be removed from the machine whenever it is desired to exhibit the pictures on a larger scale, and then the pictures may be projected upon a large screen, or directly upon the wall of the room at a considerable distance from the machine.

A smaller moving-picture machine and film may be used with a common enlarging-lens, instead of the full-size projector and film.

The voice, or other sound, will (with the 6 machine screen 13) be back of the screen, and produce a realistic effect in connection with the pictures shown on said screen.

The projecting-machine moves in positive synchronism with the talking-machine; 7 both starting at the same time from a definite starting-point marked on the film and on the record.

The machines, combined as above-described, will be simultaneously driven by a 7 single motor, which may be supplied with electricity from the ordinary electric-light wires of the house, or from a common battery; or a hand-crank, or a common spring-motor with the usual governor, may be made 8 use of to drive the combined machines.

What I claim is:

In a combined picture-projecting and sound-reproducing machine, a casing having an opening in its front, a combined sliding-horn and screen-support mounted to slide in said opening of the casing, a screen carried by the outer end of said combined sliding-horn and screen-support and disposed across said opening, a picture-projecting machine in the rear of said casing and adapted to project a picture onto said screen, and a sound-reproducing device supported above said sliding-horn and screen-support and having a horn which connects with the 95 interior of the said sliding-horn and screen-support and thereby directs the sound waves downwardly and forwardly into the said sliding-horn and screen-support.

In testimony whereof, I have signed my 10 name to this specification, in presence of two subscribing witnesses.

JOSEPH MOLTCHEN.

Witnesses:

HENRY L. HIGDON,
JOHN C. HIGDON.
